By. *Edward A. Strauss*. Atty.

UNITED STATES PATENT OFFICE.

FRANK P. LAMAR, OF SANTA ANA, CALIFORNIA.

OIL-FEED-SIGNAL DEVICE.

1,229,097.

Specification of Letters Patent. Patented June 5, 1917.

Application filed May 13, 1916. Serial No. 97,321.

To all whom it may concern:

Be it known that I, FRANK P. LAMAR, a citizen of the United States, residing at Santa Ana, in the county of Orange, State of California, have invented new and useful Improvements in Oil-Fee-Signal Devices, of which the following is a specification.

This invention relates to an oil feed signal device, and pertains especially to a device for indicating the flow of oil through an oil system.

It is an object of this invention to provide a signal system of the character above described with a mechanically actuated means for controlling a perceptible signal.

It is another object of this invention to provide an oil feed signal device with a mechanism operated by the weight of oil in a cup.

It is a further object of this invention to provide an oil feed signal device with mechanism having a cup for containing oil so arranged that the amount of oil therein is dependent upon the flow of oil through the mechanism or the level of oil therein.

I accomplish these objects by means of the embodiment of my invention illustrated in the accompanying drawing, in which:

Figure 1 is a fragmentary view of the mechanism mounted upon the front end of an automobile, and having my improved oil feed signal device attached thereto.

Fig. 2 is an enlarged vertical sectional view of the oil feed signal device.

Fig. 3 is a section as seen on the line 3—3 of Fig. 2.

Referring more particularly to the drawing, 4 indicates generally the front end of an automobile having mounted thereon an engine 5 provided with a crank case sump 6. The suction side of a pump 7 is connected to the sump and forces oil through discharge piping 8, and piping 9 to the distribution points for the oil. Connected between the piping 8 and piping 9 is my improved oil feed signal device 10.

The oil feed signal device is preferably comprised of a cylindrical receptacle 11 provided at its upper edges with an outwardly extending flange 12 having suitable apertures for receiving bolts. The lower wall of the receptacle 11 has a nipple 13 threaded for connection with the piping 9 and provided with a port 14 for the outflow of oil. A boss 15 is formed upon the lower wall and is bored, as indicated at 16 to re-

ceive a stem. The upper end of the receptacle 11 is closed by a cover 17 which is provided with a threaded nipple 18 suitable for connecting the discharge piping 8 thereto and provided with a bore 19 for the inlet of oil. Apertures are provided in the cover 17 registering with apertures in flange 12. Bolts are disposed in registering apertures to secure the cover to the receptacle.

At the center of the cover 17 on the inner side thereof are arms 20 extending downwardly and forming a stem guide. Between the point of attachment of the arms 20 in the cover 17 is formed an aperture 21 which is threaded and adapted to receive an insulating plug 22. Plug 22 is apertured at its center, and has extending therethrough a post 23 having a head 24 at its lower end, thereby providing an electrical contact. The post 23 is threaded and mounted thereon is a threaded washer 25 to coöperate with head 24 for securing the post to the insulating plug. A nut 26 is mounted upon the post 23, thereby providing means for attaching an electrical conductor to the post.

Mounted within the receptacle 11 is a cup 27 of cylindrical form, and of such dimensions that its side wall is spaced from the side wall of the receptacle 11, thereby permitting free movement of the cup 27 upwardly or downwardly and a space through which oil may flow. A leak port 28 is provided in the lower wall of the cup 27 and permits the outflow of oil from the cup. Secured to the cup is a stem 29 which extends downwardly and is disposed in the bore 16. The upper end of the stem 29 is disposed between the guide arms 20 and forms an electrical contact which coöperates with the contact formed by head 24 on the post 23. The bore 16 also acts as a guide means for the stem 29. Disposed between the walls of the cup 27 and the receptacle 11 is a compression spring 30 which tends to hold the cup 27 in its upper position.

Oil is forced by the pump through the port 19 and into the receptacle 11. The port 19 being disposed above the cup 27 the oil flows into the cup, and if the rate of flow is sufficient it fills the cup, overflows the edges and passes between the side wall of the cup and the receptacle 11 into the lower part of the receptacle and out through the port 14. Some oil passes through the leak port 28 in the cup but if the rate of flow of oil is normal the amount which passes

into the cup is greater than that which will flow through the leak port 28.

The weight of the oil in the cup 27 compresses the spring 30 and maintains the cup

5 in the position shown in full lines in Fig.

2. If the flow decreases, so that the amount passing through port 19 is not as great as will pass through the leak port 28, then the level of the oil in the leak cup lowers and

10 the weight of the oil therein is overcome by the expansive force of the spring 30 which forces the cup upwardly into the position shown in dotted lines in Fig. 2. In its movement upwardly stem 29 which forms one

15 contact of a make and break engages head 24 which forms the other contact.

I have shown an electrical conductor 31 which is connected to the post 23 and leads to one terminal of lamp 33, preferably

20 mounted on the dash board. The other terminal of the lamp 33 is connected by a conductor 34 to a generator 32 operated by the automobile engine. The other terminal of the generator 32 is grounded upon the

25 frame of the automobile as indicated at 35. Engagement of the stem 29 and head 24 completes an electric circuit from the generator 32 through conductor 34, lamp 33, conductor 31 to post 25, through stem 29 which

30 is in electrical contact with the receptacle 11 and its cover 17. As the receptacle 11 and cover 17 are connected by metallic piping to the crank case 6 and the automobile frame, electrical connection is formed be-

35 tween the receptacle 11, cover 17, and the other terminal of the generator 32 through

ground 35, completing the circuit. It is obvious that a decrease in the flow of oil if sufficient will cause the signal de-

40 vice 10 to make the circuit and light the lamp on the dash board, thereby indicating that the flow of oil is decreased. Any other perceptible signal than a lamp may be used, such as a bell, whistle, or horn. It is also

45 within the scope of my invention to employ a signal pneumatically operated which may be controlled by the stem 24 operating a valve. I do not wish to limit myself to any

particular type of perceptible signal.

50 What I claim is:

1. A signal device for oiling systems, comprising a closed receptacle having an inlet port for oil at its upper end, and a discharge

port for oil at its lower end; a cup disposed

55 in said receptacle to receive oil from said inlet port, said cup provided with a leak

port at its lower end, the side walls of said

receptacle and cup being spaced to permit

passage of oil and movement of said cup;

60 resilient means tending to hold said cup in

its upper position; and a control means for a perceptible signal operatively connected to said cup for operating said signal when the cup is in its upper position.

2. A signal device for oiling systems, comprising 65 a closed receptacle having an inlet port for oil at its upper end, and a discharge

port for oil at its lower end; a cup disposed

in said receptacle to receive oil from said

inlet port, said cup provided with a leak 70

port at its lower end, the side walls of said

receptacle and cup being spaced to permit

passage of oil and movement of said cup;

resilient means tending to hold said cup in

its upper position; and a make and break 75

device operatively connected to said cup and

interposed in an electric circuit, said re-

silient means normally tending to maintain

said make and break device closed.

3. A signal device for oiling systems, com-

prising a closed receptacle having an inlet

port for oil at its upper end, a discharge

port for oil at its lower end, and a bore in

the bottom of said receptacle; a cup dis-

posed in said receptacle to receive oil from

85 said inlet port, said cup provided with a

leak port at its lower end, the side walls of

said receptacle and cup being disposed to

permit passage of oil and movement of said

cup; a stem secured to said cup extending

90 downwardly into said bore, and upwardly

to form an electrical contact; a complemen-

tary contact insulated from and secured to

the top wall of said receptacle; and resil-

ient means tending to maintain said contacts in

95 closed position.

4. A signal device for oiling systems, com-

prising a closed receptacle having an inlet

port for oil at its upper end, a discharge

port for oil at its lower end, a bore in the

100 bottom of said receptacle, and a stem guide

upon the upper wall of said receptacle; a

cup disposed in said receptacle to receive

oil from said inlet port, said cup provided

105 with a leak port at its lower end, the side

walls of said receptacle and cup being

spaced to permit passage of oil and move-

ment of said cup; a stem secured to said cup

extending downwardly into said bore and

upwardly into said guide forming an elec-

trical contact; a complementary contact in-

sulated from and secured to the top wall of

said receptacle; and a helical spring dis-

posed about said stem and abutting the lower

wall of said receptacle and said cup tending

115 to maintain said contacts in closed position.

In witness that I claim the foregoing I

have hereunto subscribed my name this 24th

day of April, 1916.

FRANK P. LAMAR.
